US00D830964S

(12) **United States Design Patent** (10) **Patent No.:** **US D830,964 S**
(45) **Date of Patent:** **** Oct. 16, 2018**

(54) **BATTERY FOR AN ELECTRONIC DEVICE**

(71) Applicant: **Apple Inc.**, Cupertino, CA (US)

(72) Inventors: **Shota Aoyagi**, San Francisco, CA (US); **Jeremy Bataillou**, San Francisco, CA (US); **Sina Bigdeli**, Saratoga, CA (US); **Richard Hung Minh Dinh**, San Jose, CA (US); **Richard P. Howarth**, San Francisco, CA (US); **Kurtis James Mundell**, San Francisco, CA (US); **Scott A. Myers**, San Francisco, CA (US); **Benjamin J. Pope**, Sunnyvale, CA (US); **Clement Tissandier**, San Francisco, CA (US)

(73) Assignee: **Apple Inc.**, Cupertino, CA (US)

(**) Term: **15 Years**

(21) Appl. No.: **29/576,681**

(22) Filed: **Sep. 6, 2016**

(51) LOC (11) Cl. **13-02**

(52) U.S. Cl.

USPC **D13/103**

(57) **CLAIM**

The ornamental design for a battery for an electronic device, as shown.

DESCRIPTION

FIG. 1 is a front perspective view of a battery for an electronic device showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view of a battery for an electronic device showing the claimed design;

FIG. 10 is a bottom rear perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

The broken lines in the figures and the areas within the broken lines show portions of the battery for an electronic device that form no part of the claimed design.

1 Claim, 16 Drawing Sheets
